UNITED STATES PATENT OFFICE.

EDWIN M. ROSENBLUTH, OF PHILADELPHIA, PENNSYLVANIA.

DESIGN FOR A COMBINATION LAMP AND LICENSE-TAG BRACKET.

41,637.

Specification for Design.

Patented Aug. 1, 1911.

Application filed April 30, 1910. Serial No. 558,738. Term of patent 14 years.

To all whom it may concern:

Be it known that I, EDWIN M. ROSENBLUTH, of Philadelphia, in the State of Pennsylvania, have invented a new, original, and ornamental Design for Combination Lamp and License-Tag Brackets, whereof the following is a specification, reference being had to the accompanying drawing.

In the drawing; Figure I is a plan view of a bracket showing my design and Fig. II is an outer front view of said bracket.

This design relates to lamp brackets of the general class contemplated in Letters Patent of the United States #883,973

granted to me April 7th, 1908 and comprises a horizontal base having a socket, and, arms including vertical standards upon opposite sides thereof having curved portions merging into said body.

I claim:

The ornamental design for a combination lamp and license tag bracket, as shown and described.

EDWIN M. ROSENBLUTH.
